UNITED STATES PATENT OFFICE.

HENRY CLASEN AND CHARLIE NOESLER, OF MINDORO, WISCONSIN.

WINDMILL-COUPING.

1,245,683.

Specification of Letters Patent.

Patented Nov. 6, 1917.

Application filed March 7, 1917. Serial No. 153,187.

To all whom it may concern:

Be it known that we, HENRY CLASEN and CHARLIE NOESLER, citizens of the United States, residing at Mindoro, in the county 5 of La Crosse, State of Wisconsin, have invented a new and useful Windmill-Coupling; and we do hereby declare the following to be a full, clear, and exact description of the invention, such as will enable others 10 skilled in the art to which it appertains to make and use the same.

This invention is a device designed for use in connecting a wind mill with its pump.

Its principal object is to provide means 15 for quickly and easily disconnecting the pump from the mill, so that the pump may be operated by hand.

Another object is to provide a separable connection between the reciprocating rod of 20 the wind mill and the pump plunger that will positively couple the two together.

As a third object, provision is made for the easy uncoupling of the mill and pump by the shifting of a hand operated lever.

25 In setting forth this invention a definite plan of construction has been adhered to, but the invention is not to be restricted to this especial structure. The right is reserved to vary the details of construction to 30 meet the demands of practice, so long as these variations are comprehended in spirit by the appended claims.

In the drawings the same numerals of reference are used to designate the same parts 35 throughout the several figures, wherein:

Figure 1 is an elevation showing the manner in which the coupler is to be used in connecting a conventional wind mill to its associated pump.

40 Fig. 2 is an enlarged side elevation of the coupler.

Fig. 3 is a longitudinal section of the same.

Fig. 4 is a section on the line 4—4 of 45 Fig. 3.

Fig. 5 is a plan of the hand lever used to operate the coupler.

Fig. 1 shows a conventional wind mill having the wind wheel 1, the supporting 50 members 2, the platform 3 and the reciprocating rods 4 and 5. It is, of course, understood that this wind mill has in addition to the parts mentioned all the appurtenances necessary to make it complete and to enable 55 it to impart a reciprocating motion to the rod 4. Fig. 1 also shows a conventional

pump 6 with its attendant plunger 7 and handle 8.

The coupler comprises the channel piece 9, the flat spring 10 and the rod 11 which 60 is an integral part of the pump plunger. The channel piece 9 is designed for attachment to the rod 4, the bolts 12 with their nuts 13 serving to effect this attachment and also the attachment of the flat spring 10 65 against the web of the channel piece 9.

At the end remote from the rod 4, the channel piece 9 has a short channel piece 14 attached, the flanges of 14 attaching to the flanges of 9 by any acceptable means. The 70

channel piece 14 operates as a keeper for rod 11, so that the latter is always retained in close but slideable contact with the flanges and web of the channel piece 9. At a point above where piece 14 is connected, suitable 75 pivotable connections 16 are provided on which the arms 17 of the hand lever 15 are supported. The arms 17 are integral parts of the lever 15 which has also handle 18. The spread of the arms 17 is equal to the 80 width of the channel piece 9 outside its flanges and these arms are adapted to receive at their ends the small shaft 19 on which the roll 20 is capable of turning, the shaft 19 being held frictionally in the eyes 85 of the arms 17.

The flat spring 10, for the greater part of its length, lies normally against the web of the channel piece 9. At a certain point it is turned at right angles away from channel piece 9 and then turned back so as to parallel channel piece 9, turning away again from channel piece 9 at right angles to form the narrow flange 21 on which the web of the channel piece 22 rests. That part 24 of 90 the spring 10 which parallels the channel piece 9 slants diagonally away from 9 near the point where it merges into the right angled bend 23.

A stud 25 having a shoulder portion 26 100 and a short projection 27 emanating from the shoulder portion is connected to the spring 10 and to the channel 22, the peening over of the head of 27, after it has passed through holes in the web of channel piece 105 22 and that end of spring 10 near 21, serving to hold the stud 25, the channel piece 22 and the flat spring 10 together.

In the web of channel piece 14 a hole is 110 provided and, likewise, in the web of channel piece 9 a similar hole is made. Both these holes are in alignment and are adapted

to register with the stud 25, when the latter is in its normal position.

The rod 11 is an integral part of the pump plunger, as shown in Fig. 1. This rod is 5 provided with a hole or holes through which the stud 25 is designed to pass when effecting the coupling operation.

In Fig. 1 the device is shown connecting the reciprocating rod of a wind mill with 10 the plunger of a pump, the position of the stud 25 being such that it maintains the rod 11 in positive connection with channel member 9, so that any movement of rod 4 will, thereby, be transmitted to the pump 15 plunger.

When it is desired to uncouple the pump from the mill, the lever 15 is operated by pulling down on its handle 18. A movement downward of this handle 18 results, by 20 virtue of the pivotal connection 16, in an upward movement of the roll 20 which, pressing against that part 24 of the spring 10, serves to disengage the stud 25 on both 25 the channel piece 9 and the rod 11. The position assumed by the parts after the uncoupling operation is shown in dotted lines in Fig. 2. The acute angle formed at the junction of the bends 23 and 24 of the spring 10 forms a means for retaining the roller 20 30 in the position assumed after the uncoupling operation, while the small flanges 29 serve as a limiting means to prevent the spring 10 and channel 22 from being moved too far out of position.

35 The invention having been set forth, what is claimed as new and useful, is:—

1. In a device for coupling wind mills and the like, a channel member adapted to engage the reciprocating rod of a wind 40 mill, a pump plunger in sliding engagement between the flanges of the channel member, means in surrounding relation to the pump plunger for insuring the sliding relation between it and the channel member, said 45 means having oppositely disposed holes, said pump plunger having a hole adapted to register with said oppositely disposed holes, a flat resilient member adjacent to the longitudinal edge of the channel mem- 50 ber, said resilient member having an offset end formed by bending it at right angles on itself with the bent portion turned back into a plane parallel with the channel mem- 55 ber, an acute angle obtaining at the junction of the offset end and right angled bend, a stud carried by said offset end and adapt-

ed to register with said oppositely disposed holes and said hole in said pump plunger for effecting a positive connection between said channel member and said pump plunger, and means pivoted to said channel member for shifting the position of said resilient member and said stud with respect to said pump plunger and to said surrounding means therefor, said means comprising a U-shaped lever whose legs straddle the channel member, a shaft supported between the ends of the legs of said U-shaped lever and a roll carried by said shaft and rotatable thereon, said roll being adapted to 60 rest in the acute angle formed in the offset end to hold said stud out of engagement with said pump plunger. 65

2. In a device for coupling wind mills and the like, a channel member adapted to 70 engage the reciprocating rod of a wind mill, a pump plunger in sliding engagement between the flanges of the channel member, means in surrounding relation to the pump plunger for insuring the sliding relation 75 between it and the channel member, said means having oppositely disposed holes, said pump plunger having a hole adapted to register with said oppositely disposed holes, a flat resilient member adjacent to the 80 longitudinal edge of the channel member and having an offset end, a stud carried by said offset end and adapted to register with said oppositely disposed holes and said hole in said pump plunger for effecting a posi- 85 tive connection between said channel member and said pump plunger, a guide piece carried by said offset end and substantially surrounding said stud and said means surrounding the pump plunger, and means piv- 90 otted to said channel member for shifting the position of said resilient member and said stud with respect to said pump plunger and to said surrounding means therefor, said means comprising a U-shaped lever 95 whose legs straddle the channel member, a shaft supported between the ends of the leg of said U-shaped lever and a roll carried by said shaft and rotatable thereon. 100

In testimony whereof we have signed our 105 names to this specification in the presence of two subscribing witnesses.

HENRY CLASEN.
CHARLIE NOESLER.
